FIG. 2.

INVENTOR.
C. S. Bushnell,
BY Neil D. Weston,
his ATTORNEY

UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

CONTINUOUS INDUCTIVE TRAIN CONTROL.

Application filed September 20, 1924. Serial No. 738,878.

This invention relates to automatic train control systems for railways, and more particularly to the provision of suitable automatic means which requires the engineer to 5 take appropriate action, conveniently termed acknowledgment, at or near each stop signal, otherwise an automatic application of the brakes occurs and the train is brought to a stop, or other suitable penalty is inflicted.

More specifically, in accordance with the present invention, it is proposed to require the engineer to perform an acknowledging act at successive points or intervals of distance in the travel of the train while running under a stop signal through a danger or occupied block. It is proposed to select an interval of distance for such recurrent acknowledgment as will cause the acknowledgment to take place at the first stop signal encountered by a train and at, or closely adjacent to the succeeding stop signals. In the form of the invention illustrated, acknowledgment of each caution 25 signal is required, in addition to the acknowledgment of successive stop signals; but obviously the acknowledgment of the stop signals may be used alone, if desired.

With the idea of facilitating traffic, and 30 for other reasons, it is proposed in this invention to eliminate the stopping of the train or other penalty for failure to acknowledge if traffic conditions clear up in the meantime.

35 In order to protect the acknowledging device from abuse, according to this invention, the engineer must restore this device to its normal or inactive condition in order to consummate the acknowledging act, with 40 the result that he cannot defeat the purposes of the device by permanently holding or fastening it in the active acknowledging position.

45 Other objects, purposes and characteristic features of this invention will appear as the description thereof progresses.

In describing the invention in detail reference will be made to the accompanying drawings in which:—

50 Fig. 1 illustrates an especially simple railway signaling system, upon which the trackway apparatus for a simple form of automatic train control system embodying the present invention has been superimposed; and

Fig. 2 illustrates conventionally and in a diagrammatic and perspective manner one form of car-carried apparatus embodying the present invention.

Although the present invention is applicable to various types of train control systems, such as intermittent systems of various kinds and continuous inductive systems of the three-position type, it has been shown applied to a simple form of two-position 60 continuous inductive train control system so as to simplify the illustration and description thereof.

Referring to Fig. 1, the reference characters 1 designate the usual track rails which are divided by insulating joints 2 into blocks in the usual way, the block I and the adjacent ends of the blocks H and J only being shown. Since the various blocks are assumed to be equipped the same, like parts 70 of each block are designated by like reference characters having distinctive exponents. Using the reference numbers for the block I, each block has connected across its rails at the exit end thereof the usual track 80 battery 3 connected in series with the usual limiting resistance 4; and the entrance end of each block has bridged across the rails thereof the usual track relay 5, which is in this case a direct current relay. Although 85 the present train control system may be used either with or without wayside signals of any suitable type, signals Z of the semaphore type have been illustrated for convenience, without showing their well known 90 operating mechanism and control circuits.

In addition to the usual signaling apparatus thus far described, alternating current is superimposed upon the direct current in the track circuit by the transformer 6, having its secondary winding connected in series with the battery 3, and having its primary winding connected to the transmission line 7 through a front contact 8¹ of the track relay 5¹ of the block J next in advance. 100

On the railway vehicle or locomotive, which has been conventionally illustrated by wheels and axles 10 and 11, is a main control relay MR, which is adapted to respond to the presence and absence, respectively, of alternating current flowing in the track rails ahead of the vehicle. In the particular arrangement shown, this main relay MR is connected to the output side of an amplifying device A, which includes suitable am- 105

plifying tubes or audions, sources of energy, tuning devices and the like. The input side of the amplifier A is connected to the coils 12 and 13 on laminated car elements 14 and 15 which are disposed directly over the rails ahead of the train. These coils 12 and 13 are connected in series, so that voltages induced therein due to current flowing in one direction in one rail and in the other direction in the other rail are cumulative and these coils are preferably tuned to resonance for the particular frequency used, by bridging across the leads thereof the condenser 16 of the proper capacity. Although the coils 12 and 13 have been shown surrounding cores of laminated magnetic material, these cores may be omitted in practice, if desired, depending somewhat on the type of amplifying device and the frequency of the alternating current used.

Referring to Fig. 1, it will be noted that the main relay MR assumes its energized position when the train is moving in a clear block, in which position it has been illustrated. If the train is in a caution block, the main relay MR assumes its de-energized position, because no alternating current is present in the track rails directly ahead of the train by reason of the fact that the track relay of the block next in advance, under the assumed caution condition, in the de-energized position, and the transformer 6 is disconnected from the transmission line 7. On the other hand, when the train in question follows another train in the same block, it is deprived of alternating current even if such current is applied to the exit end of the block, because such alternating current is shunted away from the following train in question by another said train ahead in the same block. The response of this main relay MR to changes in traffic conditions ahead should be borne in mind in connection with the description of the car apparatus in Fig. 2.

Referring to Fig. 2 of the drawings, carried apparatus of the well known cam and governor type has been illustrated; and since the various elements of the speed control apparatus are well understood by those skilled in the art and are described in considerable detail in the application of W. K. Howe, Ser. No. 38,132 filed July 6, 1915, this apparatus will only be briefly described.

In the arrangement shown, a centrifugal speed responsive device or centrifuge C is supported on a shaft 20 driven from the wheels of the vehicle in any suitable manner. The grooved collar 21 of the centrifuge C moves downwardly as the speed of the vehicle increases, so that the speed shaft 22, which is operatively connected to this collar 21 by the bifurcated arm 23, is rocked in a clockwise direction as the speed increases to a position depending on the speed of the train. In the particular position of the ap-

paratus illustrated, the speed of the train is above the minimum speed enforced by this speed control apparatus, which minimum speed is assumed to be 15 miles per hour. Fixed on the shaft 20, driven from the wheels of the vehicle, is a worm 24, which is in continuous meshed relation with a worm wheel 25 pinned to a shaft 26. A pinion 27, pinned to the shaft 26 is in continuous meshed relation with gears 28 and 29 which are pivotally supported on journals 30 and 31, respectively. A bifurcated or forked arm 32 has its bifurcated end straddling the gear 28 and is pivotally secured on the journal 30, so that this arm may swing concentrically with the gear 28 about the journal 30. In the bifurcation of this arm is pivotally journaled a pinion 33 in a manner so that it continuously meshes with the gear 28. This arm 32 is urged upwardly by a tension spring 34 but is normally held in its lower position, against the tension of this spring, by the armature 35 attracted by the speed control cam starter magnet CSS. Similarly, a pinion 36 is carried in the bifurcated arm 37 held in its lower position by an acknowledging cam starter magnet CSA, the arm 37 being urged upwardly by a spring 38.

Directly above the pinion 33 and in alignment therewith, is disposed a mutilated gear 40, which is pinned to a distance shaft 41, so as to turn this shaft in accordance with the progress of the train while the mutilated gear 40 is in mesh with the pinion 33. To the distance shaft 41 are firmly secured for rotation therewith a permissive speed cam 42 and four distance cams 43, 44, 45 and 46. These distance cams, through suitable rollers cooperating therewith, are adapted to close contacts 47, 73, 48 and 51 respectively, during various angular positions of this distance cam shaft 41.

To the speed shaft 22 is secured a speed arm 17, to the free end of which is pivotally connected a floating lever 18, having a roller 19 at the free end thereof which rides against the cam surface of the cam 42. By observing the manner in which this floating lever 18 is supported, it is obvious that all that is necessary in order to operate suitable contacts in accordance with the speed of the train as compared with the permissive speed set up by cam 42, is to operate such contacts in accordance with the position of an intermediate point on this floating lever 18. In the particular arrangement shown, this has been accomplished by providing a sector 52, pivotally supported on a journal 53 and having an eccentrically located pin 54 thereon, which is connected to an intermediate point on the floating lever 18 by a link 88. This sector 52 is biased in a counter-clockwise direction by the spring 39 and is shaped so as to cause contacts 83 to open when the

actual speed of the train is higher than the permissive speed set up by the permissive speed cam 42.

In like manner, another distance shaft, 5 conveniently called and acknowledging shaft 55 is adapted to be rotated by the pinion 36 through a gear 56 fixedly secured on this shaft 55, when the acknowledging cam starter magnet CSA is de-energized. This 10 acknowledging shaft 55 has distance cams 57, 58, 59 and 60 fixedly secured thereto so as to rotate therewith; and these distance cams are adapted, through the medium of rollers engaging the surface of these cams to operate 15 contacts 61, 62, 63 and 64, respectively, at various angular positions of the acknowledging shaft 55.

Since the present invention does not relate to any particular type of apparatus for applying the brakes of the usual air brake system, no specific type of device for carrying out this function has been illustrated. An electro-pneumatic valve EPV has, however, been shown, which may be used to actuate 25 the usual engineer's brake valve in a manner so that the engineer may not prevent its operation, or which may be used to operate a suitable application valve, which vents the brake pipe and cuts the main reservoir 30 pressure off the engineer's brake valve so that he cannot recharge the brake pipe while this application valve is in its active position.

The acknowledging device or contractor is shown as a simple button PB, resilient or 35 spring returned, and having normally open and normally closed contacts. This push button PB is located at some convenient point in the cab and in easy reach of the engineer, and is enclosed in a suitable locked 40 or sealed casing, with only an operating member projecting, so that the engineer cannot interfere with the electrical connections.

Operation.

45 In order to describe the operation of the system in detail, it is considered advisable to first trace all of the essential closed circuits, after which the various steps in the operation may be taken up.

50 Under normal clear traffic conditions, the car-carried apparatus is in the condition illustrated. The speed control cam starter magnet CSS is energized by a circuit leading from the terminal B of a suitable source of energy, which has its other terminal connected to a common return wire C, which circuit includes a front contact 65 of the main control relay MR. With the distance shaft 41 in its normal position by reason of the energization of the cam starter magnet CSS, the cam starter magnet for the acknowledging shaft 55 is energized through a circuit as follows:—Beginning at the terminal B of a suitable source of energy, wire 66, contacts 65 47 operated by the distance cam 43, wire

67, contacts 61 operated by the distance cam 57, wire 68, winding of the cam starter magnet CSA, wire 69 back to common return wire C to the other terminal of said source.

The penalty relay PR is normally energized by the following circuit:—beginning at the terminal B, wire 72, contacts 73 and 49 of the distance cam 44, wires 74 and 75, contacts 51 of the distance cam 46, wires 76 and 77, front contact 78 of the penalty relay PR, wires 79 and 80, winding of the penalty relay PR, wire 81, back to the common return wire C. There are several other circuits by which the penalty relay PR is normally energized, but these can more advantageously be considered hereinafter.

Under normal conditions of the apparatus when the train is moving at an intermediate speed, as heretofore assumed, the electro-pneumatic brake control device EPV is energized through the following circuit:—beginning at the terminal B, wire 82, cam and governor contacts 83, wire 84, front contact 85 of the penalty relay PR, wire 86, winding of the device EPV, wire 87, back to common return wire C. From this circuit, it will be noted that the device EPV is de-energized if either the governor-cam contacts 83 or the front contact 85 of the penalty relay PR are opened.

Maximum speed limit.—While the train is traveling in a clear block, the brakes are automatically applied if a predetermined maximum speed is exceeded. Referring to Fig. 2, it will be evident that, after a certain speed has been reached, the lower end of the floating lever 17 will have been moved far enough to the left, with the cam 42 in the normal initial position shown, to cause opening of the contacts 83, thereby de-energizing the brake controlling valve EPV. As soon as the speed of the train is brought down by such automatic brake application below the maximum normal running speed, the contacts 83 close again, the valve EPV 110 is again energized, and the engineer may release the brakes. Consequently, there is no particular penalty for exceeding the maximum speed limit under clear traffic conditions.

Caution block.—Let us now consider the operation of the car-carried apparatus, as the train moves from the block H which is assumed to be clear toward the right when the block J next in advance is occupied, that is, when the block I is a caution block. As the train moves into the block I, the main relay MR assumes its de-energized position, the cam starter magnet CSS is de-energized, and the pinion 33 125 comes into meshed relation with the milled gear 40, turning the distance shaft 41 in one direction or the other depending on whether the train is moving pilot or tender first. After a short distance of movement 130

4
of the train, as indicated by the horizontal line 48 in Fig. 1 of the drawings, the contacts 48 operated by the distance cam 45 close. The closure of these contacts causes 5 the acknowledging signal Ack S to sound, giving the engineer a warning that he must now manifest his vigilance by operating the acknowledging push button PB in order to avoid an automatic brake application. The 10 circuit for sounding this signal may be traced as follows:—beginning at the terminal B, wire 90, contacts 48 operated by distance cam 45, wires 91 and 92, back contact 93 of the acknowledging relay Ack R, 15 wire 94, acknowledging signal Ack S, wire 95 back to common return wire C.

Proceeding on the assumption that the engineer is vigilant and responds promptly by depressing the push button PB, a pick-up circuit for the acknowledging relay Ack R is completed as follows:—beginning at the terminal B, wire 96, acknowledging push button PB, wires 97 and 98, winding of the acknowledging relay Ack R, wire 99, back to common return wire C. With this acknowledging relay Ack R once picked up, a stick circuit for this device is completed which may be traced as follows:—beginning at the terminal B, wire 90, contacts 48 of the distance cam 45, wires 91 and 92, contact 93 of the acknowledging relay Ack R in its raised position, wires 100, 101 and 98, winding of the acknowledging relay Ack R, wire 99, back to common return wire C. It should be noted that the acknowledging signal is discontinued as soon as the acknowledging relay Ack R is energized, because the acknowledging signal circuit includes the back contact of armature 93 of this relay.

After a further short distance of travel, as indicated by a solid portion of horizontal lines 49 and 50 in Fig. 1 compared with the horizontal line 48, the contacts 49 open and the contacts 50 close. These contacts are operated by the distance cam 44 and used for the purpose of making the requirement of acknowledgment by the acknowledging shaft 55 hereinafter to be explained effective or ineffective depending on the position of the distance shaft 41. With the contacts 49 open, the main stick circuit for the penalty relay PR heretofore traced is no longer intact, but another stick circuit which may be traced as follows maintains the penalty relay PR energized:—beginning at the terminal B, wire 104, contacts 63, operated by the acknowledging cam 59, wires 105 and 75, contacts 51 operated by the distance cam 46, wires 76 and 77, front contact 78 of the penalty relay PR, wires 79 and 80, winding of the penalty relay PR, wire 81 back to common return wire C.

After a further short distance of travel, 65 which may be observed by looking at the

horizontal lines in Fig. 1, the contacts 51 open for a short distance of travel, as indicated by the dotted portion of the line 51 (see Fig. 1). Opening of contacts 51 interrupts the stick circuit for the penalty relay PR heretofore traced, but by reason of the fact that the engineer was vigilant and operated the acknowledging push button PB, so as to energize the acknowledging relay Ack R, as has been assumed, he has completed another stick circuit for the penalty relay PR which may be traced as follows:—beginning at the terminal B, wire 96, push button contact PB, wire 108, front contact 109 of the acknowledging relay Ack R, wires 110 and 77, front contact 78 of the penalty relay PR, wires 79 and 80, winding of the penalty relay PR, wire 81 back to the common return wire C. It should be noted that this penalty relay stick circuit includes the contact of the push button PB closed in its normal position, so that the engineer is not only required to operate the push button, but is required to return it to normal so as to consummate the acknowledging act. Had the acknowledging relay not been stuck up or the acknowledging push button been returned to normal, the device EPV would have been de-energized, because of dropping of the contact 85 of the penalty relay PR. The contacts 51 are opened for a short distance of travel only (see the horizontal line 51), and a short distance of travel after these contacts 51 are again closed, the contacts 48 again open. The opening of contacts 48 breaks the stick circuit for the acknowledging relay Ack R, thereby causing this relay to again assume its normal de-energized position.

As the train now proceeds through the caution block I, the block J next in advance remaining occupied, the permissive speed set up by the permissive speed cam 42 gradually decreases, thereby requiring the engineer to reduce his speed substantially as indicated by the curve 106 (Fig. 1) to avoid an automatic brake application by opening of the cam-governor contacts 83. When the train has progressed a distance in the block to the point indicated by the vertical line 107, the distance contacts 47 open, thereby breaking the circuit for the acknowledging cam starter magnet CSA, thus causing the acknowledging cam shaft 55 to be rotated in accordance with the progress of the train through the medium of pinion 36.

After a short distance of travel with the cam starter magnet CSA de-energized, the contacts 61 open, thereby assuring that this cam starter magnet CSA is not again re-energized until the shaft 55 assumes its normal position. The gear 56 is not provided with a mutilated portion, as is the gear 40, so that the gear 56 continues to rotate so long as the train moves and the cam starter magnet 130

CSA is de-energized; whereas the mutilated gear 40 only turns against the bias of the returning spring 103 until the pinion 53 gets into the mutilated portion of this gear, after 5 which, if the cam starter magnet CSS is energized, the spring 103 returns the shaft 41 to its normal position.

At about the same point in the travel of the train just considered, that is, when contacts 61 open, the contacts 64 close. This permits the acknowledging relay to be stuck up at any time during substantially a complete rotation of the acknowledging shaft 55. The following stick circuit maintains 15 the acknowledging relay energized, if it is otherwise momentarily energized:—beginning at the terminal B of a battery, wire 125, contacts 64, wire 126, front contact 127 of the acknowledging relay, wires 128, 101 20 and 98, winding of the acknowledging relay Ack R, wire 99 and back to the common return wire C. The purpose for which these contacts 64 were provided is more readily explained hereinafter.

25 The rotation of the acknowledging shaft 55 does not change the function of the permissive speed cam 42, this speed cam continuing to reduce the permissive speed, as indicated by the curve 106, until the permissive 30 speed has been reduced to its ultimate minimum or low limit, assumed to be 15 miles per hour, as indicated by the horizontal line 111. Shortly after the train has been restricted to this minimum speed and when 35 the acknowledging shaft 55 has rotated substantially a half revolution, this acknowledging shaft closes contacts 62 (see horizontal line in Fig. 1), thereby closing a circuit for the acknowledging signal Ack S as follows:—beginning at the terminal B, wire 72, contacts 73 and 50 operated by the distance cam 44, wire 112, contact 62 operated by the acknowledging cam 58, wires 113 and 92, back contact 93 of the acknowledging 40 relay Ack R, wire 94, winding of the acknowledging signal Ack S, wire 95 back to common return wire C. The sounding of this audible acknowledging signal Ack S advises the engineer that he must manifest 45 his alertness; and if he does this by depressing the push button PB, the acknowledging relay will again be picked up and stuck up, and the acknowledging signal silenced in the same manner heretofore described.

50 Upon a further slight movement of the train the contacts 63 are opened, as indicated by the line 63 (see Fig. 1), and if the engineer had failed to operate the acknowledging device because he was incapacitated or did not attend to his duties for some other reason, opening of the contact 63 would have interrupted the auxiliary stick circuit for the penalty relay PR heretofore traced, and would have effected an automatic brake application, so as to reduce the speed of the

train as indicated by the curve 114 and bring the train to a stop. Since, as has been assumed, the engineer has performed the required acknowledging act, the penalty relay stick circuit is held closed by contact 70 109 of the acknowledging relay.

It should be borne in mind that the acknowledging relay is now stuck up through two stick circuits, one including front contact of armature 93 and the other including 75 front contact of armature 127, and that this relay will not assume its de-energized position until both of these stick circuits are broken. Upon a further short distance of movement of the train, contacts 62 again 80 open and break the stick circuit including the front contact 93. When the acknowledging shaft has substantially completed one revolution, the contacts 64 again separate and the other stick circuit of the acknowledging relay is broken and this relay 85 Ack R assumes its de-energized position.

As the train continues to move in restricted territory, that is, so long as the main relay MR is de-energized, the acknowledging 90 signal is repeatedly sounded, and acknowledgment is required for reasons just given each time the acknowledging shaft 55 completes a revolution after the acknowledging 95 just considered.

If the train again moves in clear territory and the main relay MR is re-energized, the resultant re-energization of the cam starter magnet CSS causes immediate return of distance shaft 41 to its normal position. 100 This return to the distance cam 44 to normal causes the contact 73 to again assume its normal position, as shown in the drawings, so that the operation of contacts 62 and 63 does not sound the acknowledging signal 105 Ack S or require an acknowledgment by the engineer, even though these contacts are operated by the acknowledging shaft 55, possibly because this acknowledging shaft has not yet reached its ultimate normal position. As soon as the acknowledging shaft 55 again reaches its normal position and closes contacts 61, the energizing circuit for the acknowledging cam starter magnet CSA is again completed, thus causing the pinion 110 36 and the gear 56 to be disengaged and leaving the acknowledging shaft 55 in its normal position.

If the engineer has failed to operate the acknowledging device at a point in the 120 movement of the train when such operation is required and has for this reason dropped the penalty relay PR, the device EPV is immediately de-energized and remains de-energized so long as danger traffic conditions exist, and if traffic conditions in the meantime clear up and the main relay MR again assumes its energized position, the penalty relay PR is automatically picked up and maintained up by a circuit which may be 125 130

traced as follows:—beginning at the terminal B, wire 117, front contact 118 of the penalty relay PR, wires 119, 120 and 80, winding of the penalty relay PR, wire 81, 5 back to common return wire C.

If the engineer fails to manifest his vigilance for reasons just mentioned, and the penalty relay PR and the device EPV are de-energized, and traffic conditions do not clear up until the train is brought to a stop, 10 this penalty relay PR may be picked up as soon as the train is brought to a stop by reason of the speed contacts 121 which are closed when, and so long, as the speed of the train is substantially zero. The circuit through 15 which the penalty relay PR is picked up after the train has been brought to a stop depends upon the speed at which the train is traveling when this relay PR is de-energized. Assuming that the train is traveling 20 at a high rate of speed and is entering a caution block when the engineer fails to acknowledge and thus permits the de-energization of the relay PR, the motion of the 25 train in being brought to a stop is sufficient to close the contacts 51 before the actual stop is made. In this case, after the zero speed contacts 121 are closed, the relay PR 30 is picked up at once through the following circuit:—from the battery terminal B, wire 104, contacts 63 of the cam 59, wires 105 and 75, contacts 51 of the cam 46, wire 76, contacts 121, wires 120 and 80 and the winding of the relay PR through wire 81 to the battery terminal C. If it should occur because 35 of a very high train speed at the time that acknowledgment was required that the contacts 63 are open when the train comes to a stop, the pickup circuit just traced is not completed, but the engineer may in this case 40 re-energize the penalty relay by operating the push button PB and energizing the acknowledging relay Ack R. Once energized, the acknowledging relay is stuck up 45 through a circuit including its front contact 127 and the contacts 64 of the cam 60, which stick circuit has been traced, and when the push button PB is released by the engineer 50 and returned to its normal position as shown, a pick-up circuit for the penalty relay is completed, which circuit may be traced as follows:—from the battery terminal B, wire 96, push button PB, wire 108, front contact 109 of the acknowledging relay Ack R, wire 110, zero speed contacts 121, 55 wires 120 and 80, winding of the relay PR and wire 81 to the battery terminal C. In the same manner the engineer may re-energize the penalty relay PR if he has failed to 60 acknowledge at repeated distance intervals while traveling under unfavorable traffic conditions, the stick circuit for the relay PR having been broken at the contacts 63 of the cam 59 and these contacts having remained 65 open after the train has come to a stop, due

to the slow speed of the train. If the train is moving very slowly as it first encounters unfavorable traffic conditions, and the main relay MR is first de-energized, the train may be brought to a stop upon the failure of the 70 engineer to acknowledge, while the contacts 51 of the cam 46 are still open. In this case, the engineer may re-energize the relay PR to permit a release of the brakes by depressing the push button PB as before to 75 energize the relay Ack R, which relay is now stuck up through its front contact 93 and the contacts 48 of the cam 45 through a circuit which has been traced above. The return of the push button PB to its normal 80 position closes a pick-up circuit to the relay PR through the contacts 109 and 121 as explained above. In actual practice, if the engineer has permitted the relay PR to become de-energized by reason of his failure 85 to acknowledge at the proper time, and the train is brought to a stop, if the relay PR is not at once automatically energized to permit a release of the brakes the engineer depresses the push button PB and thus obtains 90 a release from the penalty stop.

From the above it is evident that if the engineer fails to make an acknowledging act and traffic conditions immediately thereafter clear up the penalty consists only in requiring him to retard the train by reason of an automatic brake application until traffic conditions do clear up, and if traffic conditions do not immediately thereafter clear up he is penalized to a greater extent, in that 100 he is required to bring the train to a stop before he can again proceed.

It should be noted that if the stick circuit for the acknowledging relay including contacts 64 and 127 had not been provided, repeated acknowledgment would have been required if the engineer made switching movements back and forth at about a point where acknowledgment is required. By the provision of this additional stick circuit the 110 acknowledging relay if once picked up is held up for a half revolution of the shaft 115 55 in either direction from the acknowledging point and the distance the train would have to travel to drop this relay by opening contacts 64 is greater than what would occur in ordinary switching movements. In this connection it should further be noted that the provision of this contact 64 permits the engineer to make the acknowledging act 120 before it is really required, and if he does so, the acknowledging signal will not be sounded at the regular acknowledging point.

It should be noted that all of the distance cams, that is, those on the acknowledging shaft as well as those on the distance shaft 125 41 are symmetrical as far as the upper and lower halves are concerned.

This construction is used so that the permissive speed performance as well as the re- 130

quirement for acknowledgment is the same whether the engine travels pilot or tender first. In practice additional influence receiving elements are placed in the rear of the last tender axle which elements are automatically or manually substituted for the elements illustrated when the engine and tender unit travels tender first instead of pilot first as illustrated.

10 Reviewing the characteristic features of the operation of the embodiment of the invention shown, it will be observed that the enforcement of acknowledgment for the first stop signal is the result of starting the acknowledging shaft 55, resulting in the opening of the contacts 63. If the engineer fails to acknowledge, the brakes are applied automatically upon the opening of the contacts 63; and in order that the train may 20 at all times be governed on the side of safety, the system is organized such that these contacts 63 open at a point near the exit end of the block which is braking distance for the minimum speed of the system from the physical exit end of the block. As indicated in Fig. 1, the contacts 63 open at a point where, if the brakes are applied on account of the failure of the engineer to acknowledge, the train will be brought to a stop at or before 30 reaching the end of the block, as shown by the braking distance curve 114.

Since the point in the block at which the contact 63 open depends upon a point in the block where the contacts 47 open to start the shaft 55, and this point in turn depends on where the car relay MR is de-energized to start the shaft 41, it will be evident that in practice the trackway circuits for the several blocks on the railroad should be organized, 40 by following out well known expedients, such as cut-sections and the like, so that the car relay MR is de-energized at a fixed distance from the exit end of each block, providing of course the next block in advance 45 is occupied. If, as sometimes happens in practice, the proper point for de-energizing the car relay MR does not come at the entrance to each particular block, the point for acknowledgment of the caution signal may 50 be some distance either in the rear or in the advance of the wayside caution signal itself. For this reason, it is desirable to provide the acknowledging signal Ack S, preferably as an audible signal, to guide the engineer in 55 making his acknowledgments. Also, since the caution acknowledgment may not be at the wayside signal itself, such acknowledgment does not serve satisfactorily to enforce 60 vigilance on the part of the engineer in observing the wayside signals; and aside from showing that the engineer is alive and not incapacitated, the acknowledgment for the caution signal required by the system shown and described may be omitted.

65 The gear ratio driving the shaft 55 is pref-

erably selected so as to cause one rotation of this shaft during a distance of travel corresponding approximately to the normal block length, so that after passing the first stop signal, the acknowledgment enforced by the 70 next revolution of the shaft 55 will take place near the second stop signal. Such proportioning, however, is optional; and if desired, the shaft 55 may make one revolution in a relatively short distance, such as 75 1,000 feet, with the result that the engineer is required to manifest his vigilance repeatedly at relatively short recurrent intervals of distance while traveling in a danger or occupied block, irrespective of the location 80 of the wayside signals and the block entrances.

Having thus shown and described one simple type of automatic train control system in connection with which the present invention 85 has been illustrated, and having illustrated a rather specific mechanism for carrying out the idea of the present invention, it is desired to be understood that this has been done for illustrative purposes rather than 90 for the purpose of showing the exact mechanism preferably employed in practice or the range and scope of the present invention, for instance, the same general arrangement may be applied to either intermittent or three- 95 position continuous inductive type train control systems by making suitable additions and changes to adapt the invention to such systems without departing from the scope of the invention or the idea of means underlying the same.

What is claimed as new and desired to be secured by Letters Patent is:—

1. In an automatic train control system, the combination of a speed restricting device governed in accordance with traffic conditions ahead and initiated if traffic conditions ahead are dangerous so as to gradually reduce the permissive speed at which the vehicle may travel without incurring an automatic brake application, normally energized means de-energized so long as traffic conditions ahead are dangerous for applying the brakes regardless of the speed at which the train is traveling and effective a 110 predetermined distance after said speed restricting device has been initiated, and means for preventing said last mentioned means from applying the brakes effective if actuated at repeated distance intervals. 115

2. In an automatic train control system, the combination of a brake setting appliance, normally energized means maintained de-energized under unfavorable traffic conditions and acting when de-energized to require the engineer to manifest his vigilance upon the approach of his train to a signal at danger and thereafter at repeated distance intervals by actuating a manually operable device, and means for actuating said 130

brake setting appliance to effect a brake application if the engineer fails to actuate said manually operable device when required.

3. An automatic train control system comprising, a brake setting appliance, means for rendering said appliance active including a permissive speed device and an actual speed device and effective if the actual speed exceeds the permissive speed, and other means for rendering said appliance active including means moved in the same direction as long as active and effective after the train has traveled a predetermined distance in dangerous territory unless a suitable manually operable device is operated at repeated distance intervals of travel.

4. An automatic train control system comprising, a normally energized stick electro-responsive device which if de-energized effects an automatic brake application; two independent means for maintaining said device energized, one of which is effective so long as the train is traveling in clear territory and a predetermined distance in dangerous territory, and the other of which includes a device rotated in the same direction so long as traffic conditions are dangerous, which device is effective if a suitable manually operable device is operated at repeated distance intervals.

5. In an automatic train control system, vehicle-carried apparatus comprising a permissive speed means which applies the brakes of the train if the speed is excessive, means for initiating said permissive speed means under dangerous traffic conditions ahead for rendering it active after a given interval of vehicle travel from the point initiated to impose a minimum speed restriction, distance governed means rotated in the same direction so long as traffic conditions are dangerous for successively actuating a cab signal and a device for imposing an automatic brake application regardless of speed after a given distance of vehicle travel from the point at which said minimum speed restriction was imposed, and means including a manually operable member for preventing the automatic brake application regardless of speed provided said manually operable member is operated at predetermined successive intervals of vehicle travel from the point at which said minimum speed restriction was initiated.

6. An automatic train control system comprising, automatic means for effecting a brake application if the speed of the train is excessive for particular conditions of traffic ahead, means for effecting an automatic application of the brakes regardless of the speed of the train, manually operable means operable by the engineer for preventing an automatic brake application by said last mentioned means if operated just prior to the initiation of such application, means

for inflicting a penalty if an automatic brake application is effected because the engineer has failed to operate said manually operable means, and means for preventing the infliction of said penalty effective if traffic conditions ahead clear up before the train has been brought to a stop.

7. Car-carried apparatus for automatic train control systems comprising, a brake setting appliance, means for actuating said appliance to effect a brake application if the speed of the train is excessive, another means for actuating said appliance regardless of the speed of the train, means for making an acknowledging act including a manually operable acknowledging device which if momentarily operated before said another means actuates said appliance is adapted to prevent actuation of said appliance, and means for protecting said manually operable device against misuse requiring said device to be returned to its normal position in order to complete the acknowledging act.

8. Car-carried apparatus for automatic train control systems comprising, a brake setting appliance, means for actuating said appliance to effect a brake application if the speed of the train is excessive, another means for actuating said appliance regardless of the speed of the train, a stick relay which if energized prevents said another means from actuating said brake setting appliance, an acknowledging push button, a pick-up circuit for said relay including contacts closed when said push button is depressed, and a stick circuit for said relay including contacts closed when said push button is in its normal position.

9. Car-carried apparatus for automatic train control systems comprising, a brake setting appliance, means for actuating said appliance to effect a brake application if the speed of the train is excessive, another means for actuating said appliance regardless of the speed of the train, a stick relay which if energized prevents said another means from actuating said brake setting appliance, an acknowledging push button, a pick-up circuit for said relay including contacts closed when said push button is depressed, a stick circuit for said relay including contacts closed when said push button is in its normal position, and means for dropping said stick relay when said another means is no longer in condition to actuate said brake setting appliance.

10. In an automatic train control system, vehicle carried apparatus comprising a permissive speed means which applies the vehicle brakes if the speed is excessive, means for initiating said permissive speed means when dangerous traffic conditions are encountered for rendering it active after a given distance of vehicle travel from the point initiated to impose a minimum speed

restriction, a normally energized electro-responsive stick device acting when de-energized to impose a brake application and bring the vehicle to a stop, distance responsive means initiated by said permissive speed means at a pre-determined distance of vehicle travel from the point at which said permissive speed means is initiated and operated continuously when initiated so long as the vehicle is proceeding under dangerous traffic conditions ahead, apparatus associated with said permissive speed means for de-energizing said stick device substantially when said permissive speed means is initiated, apparatus associated with said distance responsive means for de-energizing said stick device at predetermined distance intervals after said distance responsive means is initiated, and manually operable means acting if operated substantially when said permissive speed means is initiated and at predetermined distance intervals after said distance responsive means is initiated to prevent the de-energization of said stick device.

11. In an automatic train control system,

vehicle carried apparatus comprising a normally energized electro-responsive stick device, acting when de-energized to initiate an automatic brake application and bring the vehicle to a stop, distance operated speed control means initiated when dangerous traffic conditions ahead are first encountered, and acting to de-energize said stick device substantially when initiated, further distance operated means, initiated by said speed control means at a predetermined distance from the point at which said speed control means is initiated, and acting when initiated to de-energize said stick device at predetermined distance intervals so long as the vehicle is proceeding under dangerous traffic conditions, and manually operable means acting if operated and returned to its normal position substantially when said speed control means is initiated and at said predetermined distance intervals under dangerous traffic conditions to maintain said stick device energized.

In testimony whereof I affix my signature.

CHARLES S. BUSHNELL.
